UNITED STATES PATENT OFFICE.

ALFRED J. MACY, OF CHICAGO, ILLINOIS, ASSIGNOR TO MACY ART PROCESS CORPORATION, A CORPORATION OF ILLINOIS.

PROCESS FOR REMOVING SHADOWS FROM STEREOSCOPIC PICTURES.

Application filed April 11, 1921. Serial No. 460,432.

To all whom it may concern:

Be it known that I, ALFRED J. MACY, a citizen of the United States, and a resident of the city of Chicago, in the county of Cook and State of Illinois, have invented 5 certain new and useful Improvements in a Process for Removing Shadows from Stereoscopic Pictures; and I do hereby declare that the following is a full, clear, and exact 10 description of the same, reference being had to the accompanying drawings, and to the numerals of reference marked thereon, which form a part of this specification.

This invention relates to a process for 15 removing shadows from stereoscopic pictures and particularly to a process whereby photographic negatives or positives, or plates from which stereoscopic pictures are to be printed, may be so treated that no shadows 20 or similar effects along sharp lines of demarcation between contrasting portions will be evident when the picture is viewed stereographically.

The process disclosed herein is especially 25 applicable in connection with the production of two-color stereoscopic pictures such as are described in my Patent 1,326,720 granted August 9, 1921. This method of stereoscopic portrayal consists of printing 30 the right and left eye views of the stereoscopic picture in complementary colors in superimposed relation, and in viewing the resultant picture through suitable color screens which are adapted to shut off a different one of said complementary colors 35 from each eye of the observer. The complementary views of any given stereoscopic picture do not exactly coincide when superimposed and it is evident that when a shadow on one of the views overlaps or is adjacent to a high light on the complementary view, the complementary colors will not be entirely faded out but one of them will predominate and a sharp line of demarcation 40 of the predominating color will be visible where high lights and shadows are contiguous along the overlapping portions.

The above effect may in certain instances 45 be partially overcome by printing the picture in colors which are not of the same complementary value, but this matter involves the objectionable feature of the appearance of the entire picture in the predominating color due to the incomplete fading 50 of the colors and consequently renders

impossible the production of true black and white pictures. If color screens of sufficiently heavy colors to fade out the objectionable shadows are used, the picture is apt to appear indistinct when viewed there- 60 through.

It is an object therefore of this invention to provide a process for the production of superimposed two color stereoscopic pictures wherein adjacent contrasting portions will 65 not produce a noticeable line of demarcation when the picture is viewed stereoscopically.

It is also an important object of this invention to provide a process whereby stereoscopic pictures comprising complementary views which are printed in superimposed relation in complementary colors may be produced in such a manner that the resulting picture, when viewed stereoscopically 75 through proper color screens, appears in black and white.

Other and further important objects of this invention will be apparent from the disclosures in the drawings and the accompanying specification.

The process of this invention is diagrammatically illustrated on the drawings and hereinafter more fully described.

On the drawings:

Fig. 1 is a diagrammatic representation 85 of the first step in preparing the left eye component of the picture.

Fig. 2 is a similar representation for the right eye component.

Fig. 3 is a diagrammatic representation 90 of the second step in the process of preparing the left eye component of the picture.

Fig. 4 is a similar representation for the right eye.

Fig. 5 is a diagrammatic representation 95 of the united components forming the complete picture.

The object chosen for illustration is a light disk at a distance in front of a dark background. Fig. 1 represents the first step in the preparation of the left eye component of the picture. This may be a printed impression on paper, an image on a screen, a photographic negative, a lantern slide, a printing block or other means of reproducing the view. No attempt therefore is made to show the article itself, but it is represented by showing diagrammatically the component of the view which can be 110

made therefrom. Similar remarks apply concerning each of the figures from Fig. 1 to Fig. 4 inclusive. Figure 5, on the other hand, because it represents the components as united after all the steps in the process are completed, shows the actual picture.

As shown on the drawings:

The reference numeral 1 indicates a photographed object which is positioned forwardly of the background 2 in such a manner that high lights prevail on the object and consequently the shaded portions 3 and 4 where the dark colors representing the background 2 overlap the light area representing the object 1 when the two component views are combined into the stereographic picture. It is these overlapping portions that if the process described herein is not followed, give use to shadows when the picture is viewed stereographically. This is due to the line of demarkation between the predominating color and the background, or between said color and the object, as the case may be. In other words, the colors along said overlapping portions are not completely faded out by their complementary color, and the process of this invention provides means whereby this line of demarcation may be eliminated.

As a specific illustration of this invention consider the case where a light colored disk at a distance in front of a dark colored background is to be stereographically represented. Assume that the goggles used are green in front of the right eye and red in front of the left eye. Then the left eye component of the stereogram, shown in Figure 1 will be printed in green. According to the prior art it would consist of only a dark-green background 2 and a white or light-green disk 1.

The right eye component would be printed in red. According to the prior art it would consist of only a dark red background 2 in Fig. 2 and a white or light-red disk 1 in that figure. If these two components are superposed, the two disks 1 will not register. Instead the disk 1 from Fig. 2 will overlap the background 2 of Fig. 1. This overlap area is represented at 3. Following the prior art there would be no difference between the area 3 and the rest of the background 2. According to my invention I make a difference by giving to area 3 a lighter character than the rest of the background. In the same way I give to the corresponding area 4 in Fig. 2 a lighter red color than the dark red color forming the rest of the background 2 in Fig. 2.

The goggles used in viewing stereograms are never of exactly complementary colors and the inks used in printing them are not exactly complementary nor do they exactly correspond to the colors of the goggles. Consequently, it is possible to see some of

the red ink through the red side of the goggles and to see some of the green ink through the green side. If this invention were not employed the effect of these defects would be that the observer looking through the goggles would see in the background to the right of the disk 1 a faint band of reddish color separated from the rest of the background by a line, which, because it is sharp, is quite noticeable. For the same reason he would be likely to see a faint greenish color to the left of the disk 1 separated from the rest of the background by a sharp line. Since the ink now available can be much more nearly fitted to the color of one goggle than the other, the observer will not ordinarily see such lines on both margins of the high lights. With very dark inks in close proximity to very light spaces, these imperfections give rise to undesirable "shadows" or "ghosts" bounded by the aforementioned sharp lines when the picture is viewed through the goggles. With lighter inks such shadows do not appear, but the parts of the picture that ought to be dark will not be if they are completely printed in light inks. This invention removes the dark ink in those places where it will mar the stereoscopic effect, but leaves it undisturbed elsewhere.

Usually the stereogram is printed from two plates, one for each component. These plates are most commonly prepared from a pair of photographs. The change in color in the overlap regions (corresponding to the areas 3 and 4 in the specific illustration) may be brought about in a variety of ways. For example, the photographs, if positives, may be reduced slightly over the desired areas; if negatives, they may be slightly intensified thereover or darkened there with a retouching pencil. If the invention is applied directly to the printing plates, they may be slightly etched to cause the selected areas to deliver less ink.

It is apparent that by the use of the process of this invention it is possible to print the pictures in inks of the proper complementary colors to completely fade out when viewed through color screens, and consequently the stereoscopic picture may be made to appear in the desired black and white with no colored lines of demarcation at those portions where any shadows overlap adjacent to high lights.

I am aware that many details may be varied in effecting the process of this invention without departing from the spirit thereof, and I therefore do not purpose limiting the patent granted otherwise than necessitated by the prior art.

I claim as my invention:

1. The process of producing stereoscopic pictures, comprising making a stereoscopic negative, making a photoengraving from

each view of the negative, eroding certain portions of the photoengravings where shadows are adjacent high lights, and printing the views from the photoengravings in superimposed relation in complementary colors.

2. The process of producing stereoscopic pictures, comprising making a stereoscopic negative, producing means from which each view of the negative may be printed in complementary colors in superimposed relation, and softening certain contrasting portions of the pictures as originally photographed prior to printing.

10 3. The process of producing stereoscopic pictures, comprising reducing certain extreme contrasting portions of the component stereoscopic images and printing said images in superimposed relationship in complementary colors.

15 4. The process of producing stereoscopic

pictures comprising photographing an object to produce stereoscopic images thereof, making a photo engraving from each of the negatives, softening certain extreme contrasting portions of the separate images, and printing the images from the photoengravings in superimposed relation in complementary colors.

20 5. The process of producing stereoscopic pictures comprising reducing extreme contrasting portions of the stereoscopic images and printing said images in superimposed relation in complementary colors.

In testimony whereof I have hereunto 35 subscribed my name in the presence of two subscribing witnesses.

ALFRED J. MACY.
